FOREIGN PATENT DOCUMENTS

WO D078742-001 * 10/2012

Primary Examiner — Angela J Lee

(74) Attorney, Agent, or Firm — Banner & Witcoff, Ltd.

(57)

CLAIM

The ornamental design for a display screen with graphical user interface, as shown and described.

DESCRIPTION

The FIGURE is a front view of a display screen with graphical user interface showing the new design.

The broken line showing of the human, the display screen and a handset is for environmental purposes only and forms no part of the claimed design.

1 Claim, 1 Drawing Sheet
